UNITED STATES PATENT OFFICE.

ALFRED C. LORDLY, OF NEW YORK, N. Y.

DESIGN FOR A HANDKERCHIEF.

SPECIFICATION forming part of **Design No. 24,871, dated November 12, 1895.**

Application filed September 24, 1895. Serial No. 563,557. Term of patent 3½ years.

To all whom it may concern:

Be it known that I, ALFRED C. LORDLY, a resident of New York, in the county of New York and State of New York, have invented and produced a new and original Design for Handkerchiefs, of which the following is a full, clear, and exact specification.

My design is illustrated by the accompanying drawing, which represents one corner of a handkerchief.

The leading feature of my design consists in a rectangular body A, provided with a black border B, the said border having thereon rep-

resentations of sprays or garlands of suitable flowers, that illustrated in the drawing being a small four-leaved flower with scrolls around the same to represent leaves.

Having thus described my invention, what I claim is—

The design for a handkerchief, substantially as herein described.

ALFRED C. LORDLY.
